MOTOR SYSTEM WITH VOLTAGE LIMITING
FEEDBACKAlbert P. Upton, Minneapolis, Minn., assignor to
Minneapolis-Honeywell Regulator Company,
Minneapolis, Minn., a corporation of Delaware

Application October 14, 1942, Serial No. 461,955

10 Claims. (Cl. 318—29)

1

The present invention relates to electronic amplifiers, and especially to amplifiers adapted for use in control apparatus.

An object of the present invention is to provide an improved control system of the type wherein an alternating potential is varied in accordance with a controlling condition, amplified, and the amplified potential is used to control recording, indicating, or controlling apparatus.

Another object of the present invention is to provide an improved amplifier circuit for such a control system.

A further object is to provide, in such an amplifier, means for substantially preventing a shift in phase between the signal applied to the amplifier input terminals and the alternating electrical energy available at the amplifier output terminals.

A further object of the present invention is to provide an improved control system of the balanced type, wherein a given change in a controlling condition produces a corresponding change in the condition of a controlled device, and wherein means are provided to balance an effect corresponding to the controlling condition against an effect corresponding to the condition of the controlled device.

A further object of the invention is to provide, in such a balanced control system, improved means for preventing hunting of the control system.

A further object of the present invention is to provide an electronic amplifier circuit including improved current limiting means of the automatic volume control type.

Other objects and advantages of my invention will become apparent from a consideration of the appended specification, claims and drawing, in which:

Figure 1 is an electrical wiring diagram of an amplifier circuit embodying the principles of my invention, and

Figure 2 is an electrical wiring diagram of a temperature control system adapted to utilize the amplifier circuit shown in Figure 1.

Referring now to Figure 1, there is shown an electronic amplifier, generally indicated at 10, having input terminals 11 and 12, output terminals 13 and 14, and power supply terminals 15 and 16. The amplifier 10 includes a first voltage amplification stage generally indicated at 20, a second voltage amplification stage 21, and a final power amplification stage 22. The amplifier 10 also includes a power supply circuit 23 of the conventional full wave rectifier type.

2

The power supply circuit 23 includes an electric discharge device 24 of the twin diode type, having anodes 25 and 26 cooperating with a common cathode 27. The anodes 25 and 26 are connected by conductors 28 and 29, respectively, to the opposite terminals of a secondary winding 30 on a transformer 31 having a primary winding 32. The primary winding 32 is connected directly to the power supply terminals 15 and 16 of the amplifier 10. The cathode 27 is indicated as being of the directly heated filament type, and is supplied with electrical energy for heating purposes from another secondary winding 33 on the transformer 31. The center tap 34 of secondary winding 30 is connected through a conductor 35 to a conductor 36, which is grounded at 37. Cathode 27 is connected to a conductor 40.

The circuits to which power is supplied by the rectifier circuit 23 are connected between the conductors 36 and 40. It will be seen that the secondary winding 30 applies a positive potential alternately to the anodes 25 and 26, and that the current flow thereby resulting in the load supplied by the power supply circuit 23 is in a direction such that conductor 40 is positive with respect to conductor 36, as indicated by the legend in the drawing. A filter condenser 41 is connected between the conductors 36 and 40. A filter network comprising resistors 42 and 43, and condensers 44 and 45, also interconnects the conductors 36 and 40. These filtering arrangements are of conventional type and their purpose is to by-pass fluctuating components appearing in the potential between the conductors 36 and 40, so that these fluctuating components will not flow in the load circuits supplied thereby.

The first voltage amplification stage 20 includes a triode 50 having an anode 51, a control electrode 52, and a cathode 53. The input circuit 40 of amplifier stage 20 may be traced from control electrode 52 through a conductor 54, a condenser 55, input terminal 11, the external connections between input terminals 11 and 12 (see Figure 2 for example), input terminal 12, conductor 36, a biasing resistor 56, and a parallel by-pass condenser 57, to cathode 53. The output circuit of the first amplification stage 20 may be traced from positive supply line 40 through resistors 42 and 43, a conductor 60, a load resistor 61, anode 51, cathode 53, and resistor 56 and its parallel by-pass condenser 57 to the negative supply line 36.

Fluctuations in the potential occurring across the load resistor 61 because of variations in the current flow therethrough are transmitted

through a blocking condenser 62 to the input circuit of the second amplification stage 21. The amplification stage 21 includes a triode 63 having an anode 64, a control electrode 65, and a cathode 66. The input circuit of the second stage 21 may be traced from control electrode 65 through a conductor 67, a resistor 68, conductor 36, and a biasing resistor 69 and its parallel by-pass condenser 10 to cathode 66. The output circuit of stage 21 may be traced from positive supply line 40 through resistor 42, a conductor 72, primary winding 73 of a coupling transformer 74, and a condenser 75 connected in parallel therewith, a conductor 76, anode 64, cathode 66, and biasing resistance 69 and its parallel by-pass condenser 10 to negative supply line 36.

The coupling transformer 74 has a secondary winding 77, which is connected in the input circuit of the final power amplification stage, as described hereinafter. The power amplification stage 22 includes an electric discharge device 80 of the twin triode type. The device 80 includes an upper triode, as it appears in the drawing, consisting of an anode 81, a control electrode 82, and a cathode 83. The twin triode 80 also includes a lower triode, consisting of an anode 84, a control electrode 85, and the same common cathode 83.

The input circuit of the upper triode may be traced from control electrode 82 through a conductor 86, the upper half of secondary winding 77, center tap 87, a conductor 88, a resistance 90, and a conductor 91 to cathode 83. The output circuit of the upper triode may be traced from positive power supply line 40 through the upper half of a secondary winding 92 on a coupling transformer 93, a conductor 94, anode 81, cathode 83, and conductors 91 and 95 to negative supply line 36.

The input circuit of the lower triode in the power amplification stage 22 may be traced from control electrode 85 through a conductor 96, the lower half of secondary winding 77, conductor 88, resistor 90, and conductor 91 to cathode 83. The output circuit of the lower triode may be traced from positive supply line 40 through the lower half of secondary winding 92, a conductor 97, anode 84, cathode 83, and conductors 91 and 95 to negative supply line 36.

A condenser 98 is connected across the terminals of transformer primary winding 92 for phase shift correction purposes. The transformer 93 is provided with a secondary winding 99 which is directly connected to the amplifier output terminals 13 and 14.

From the foregoing description, it will be apparent to those skilled in the art that the final power amplification stage 22 includes two electrical discharge devices, namely, the upper and lower triodes of the twin triode 80, which are connected in what is commonly termed a push-pull circuit. These two triodes are hereinafter described in this application as being connected in phase opposition. This latter phrase is intended to be broad enough to cover not only push-pull circuits, but other similar connections of two discharge devices, which although not true push-pull circuits, operate in an equivalent manner in so far as a control system of the type described herein is concerned. An example of such a circuit is shown in my co-pending application No. 437,561, filed April 3, 1942, Patent No. 2,423,534, dated July 8, 1947.

While no heater filaments or power supply therefor are shown in connection with the triodes

52, 63 and the twin triode 80, it will be readily understood by those skilled in the art that the elements and connections necessary to heat the cathodes of the respective discharge devices may be readily supplied.

A connection is provided from the power amplification stage 22 to the first voltage amplification stage 20 for supplying a bias to the first stage which varies in magnitude with the input 10 to the power stage 22. The resistance 90 is common to both input circuits of the final stage 22. It will be seen that whenever the potential of either control electrode 82 or 85 is sufficiently positive with respect to cathode 83 to cause a flow 15 of current through the input circuit, that current, flowing through the resistor 90, produces a potential difference thereacross of a polarity such that the right-hand terminal of resistor 90 is positive, and its left-hand terminal negative, as indicated by the legend in the drawing. The right-hand or positive terminal of resistor 90 is connected through conductors 95 and 36, and resistance 56 to cathode 53 of the discharge device 50 in the first amplification stage 20. The left or negative terminals of resistor 90 is connected through a conductor 100, a resistance 101, conductor 102, and a resistance 103 and conductor 54 to control electrode 52 of triode 50. The resistances 101 and 103 are provided for 20 filtering purposes and cooperate with a condenser 104 connected between the left-hand terminal of resistance 101 and the negative power supply terminal 36 to by-pass any fluctuating component in the potential appearing across the resistor 90, so that only the unidirectional component of that potential is impressed, between the control electrode and cathode of the discharge device 50.

The following table shows, by way of example, values of capacitance and resistance which may be used in the amplifier circuit of Figure 1:

Reference Numeral	Quantity
41	10 microfarads.
42	5,000 ohms.
43	20,000 ohms.
45	20 microfarads.
55	.05 microfarad.
56, 69	5,000 ohms.
57, 70	.25 microfarads.
61	.25 megohm.
62	.05 microfarad.
50	.5 megohm.
68	5,000-10,000 ohms impedance.
73	.02 microfarad.
75	500 ohms impedance approx.
77	25,000 ohms.
90	3,000-8,000 ohms (designed to match impedance of tube and load).
92	500 ohms approx.
99	.02 to .05 microfarad.
98	.75,000 ohms.
101	.1 megohm.
103	.5 microfarad.
104	

Operation of Figure 1

When an alternating signal is applied to the input terminals 11 and 12, it is amplified in the stages 20, 21 and 22, and an alternating current of corresponding magnitude flows in the secondary winding 99 of coupling transformer 93, and is thereby available at the amplifier output terminals 13 and 14.

As is well known in the art, the current flowing in the secondary winding of a transformer is substantially opposite in phase to the potential applied to the primary winding. Due to the inherent inductance of the transformer, however, the secondary current is not exactly opposite in phase to the primary potential but lags the primary potential by an additional amount. It is

also well known that this tendency of the secondary current to lag increases as the load on the transformer is increased. When an inductively coupled amplifier is used in a control system, such as that described hereinafter in Figure 2, wherein the phase of the output current with respect to the phase of the input potential is material to the operation of the circuit, this lag in the coupling transformers may present serious difficulties. For example, if the lag in each of the two coupling transformers exceed 45 degrees, the total lag will exceed 90 degrees. As explained hereinafter, this might cause operation of the control system of Figure 2 in a sense exactly opposed to the desired mode of operation.

I have overcome these difficulties by connecting the potentials developed across the resistor 90 to the input circuits of the first amplification stage 20. It may be seen that when the current flowing in the secondary winding 11 of transformer 74 tends to increase, the unidirectional potential developed across resistor 90 likewise increases. This potential is employed to bias the input circuit of the first amplifier stage. The polarity of this potential, as applied to the input circuit of the first amplifier stage, is such that it reduces the gain of the amplifier stage thereby reducing the magnitude of the current flowing in the output circuit. This reduction in current flow in the first amplification stage is of course reflected in the current flow in the final power amplification stage. The net effect of this variable biasing arrangement is to tend to stabilize the magnitude of the current flowing in the output circuit with respect to the magnitude of the signal applied to the amplifier input terminals. It has been found that the overall input voltage-output current characteristic of this amplifier is such that as the input signal increases from zero to a large value, the output current rises rapidly until it reaches a predetermined value, after which a further increase in the input potential produces a very small, if any, increase in the output current. In other words, the arrangement operates to provide automatic volume control. The phase shift between the input potential and the output current is thereby limited to the phase shift which occurs at the maximum current value obtained. By properly selecting the values of the various impedances in the circuits, the phase shift may be limited to any desired maximum value.

The automatic volume control arrangement shown also operates to prevent overloading of the discharge devices, which might otherwise occur when a large signal is impressed on the amplifier circuit. If such an overload were not prevented, it might be accompanied by an actual reduction in the current flow through any of the discharge devices when the control electrode thereof became very positive. Such a condition would of course produce an undesirable distortion in the output characteristic of the amplifier.

In any amplifier circuit, regardless of the type of coupling used, a certain amount of phase shift has been found to exist between the input signal and the output signal. This phase shift has two components, one substantially constant and independent of the load on the amplifier, and the other variable with the load. The undesirable effects of the variable component may be overcome by the automatic volume control arrangement previously described. The constant component may be controlled by proper design of the circuit constants. In the present circuit, the

condensers 75 and 98 are provided to correct for this constant component. By proper design of these condensers, this constant component may be controlled within any desired limits.

Figure 2

Figure 2 shows a temperature control system which is adapted to use the amplifier disclosed in Figure 1. In Figure 2, a valve mechanism 110 is driven by a motor generally indicated at 111 through a gear train 112. The motor 111 is of the split phase type and includes a rotor 113 and a pair of field windings 114 and 115, which are displaced from each other in space phase by ninety electrical degrees. The winding 115 is continuously supplied with electrical energy from a secondary winding 116 of a transformer 117 having a primary winding 118. The primary winding may be connected to any suitable source of alternating electrical energy. The energizing circuit for motor field winding 115 may be traced from the upper terminal of transformer secondary winding 116 through conductors 120 and 121, winding 115, and a condenser 122 to the lower terminal of secondary winding 116. The motor winding 114 is supplied with alternating electrical energy from the output terminals 13 and 14 of an amplifier 10, which may be the same as the amplifier 10 shown in detail in Figure 1. The energizing circuit for motor field winding 114 may be traced from amplifier output terminal 13 through conductors 123 and 121, winding 114, and conductor 124 to output terminal 14.

The amplifier 10 of Figure 2 is supplied with electrical energy from another secondary winding 125 of the transformer 117. The power supply terminals 15 and 16 of amplifier 10 are connected to the terminals of winding 125 through conductors 126 and 127, respectively.

The transformer 117 has a third secondary winding 128, which supplies electrical energy to a bridge circuit shown generally at 130. The bridge circuit 130 has a pair of input terminals 131 and 132, and a pair of output terminals 133 and 134. The input terminals 131 and 132 are connected to the terminals of secondary winding 128 by means of conductors 135 and 136, respectively. The output terminals 133 and 134 are connected to the amplifier input terminals 11 and 12 by means of conductors 137 and 138, respectively.

The upper left arm of the bridge circuit 130, as it appears in the drawing, may be traced from input terminal 131 through a fixed resistance 140 and a variable resistance 141 to output terminal 133.

The upper right arm of bridge circuit 130 may be traced from input terminal 132 through a conductor 142, and a temperature responsive resistance element 143 to output terminal 133. The resistance element 143 is preferably constructed of nickel or some other material having an appreciable temperature coefficient of resistance.

The lower left arm of resistance bridge 130 may be traced from input terminal 131 through a fixed resistance 144, a portion of a slide wire resistance 145 and a slider 146 cooperating therewith to output terminal 134. The lower right arm of bridge circuit 130 may be traced from input terminal 132 through a fixed resistance 147 and a portion of slide wire resistance 145 and slider 146 to output terminal 134.

The resistance element 143 is exposed to the air in a space whose temperature is to be controlled, and the valve mechanism 110 controls the supply of a heating fluid to that space. The valve 110

may, for example, control the flow of steam to a radiator located in the space in question, or it may control the supply of fuel to a heater. In any event, the valve mechanism 110 may be located remotely with respect to the resistance element 143.

The slider 146 is operatively connected to the gear train 112 so that it is moved over the slide wire resistance 146 concurrently with the adjustment of the valve mechanism 110. The slide wire resistance 145 and the slider 146 together constitute a follow-up controller 150.

Operation of Figure 2

When the parts are in the positions shown in the drawing, the valve mechanism 110 is in its half-open position, as is indicated by the fact that the slider 146 is at a central position with respect to its range of travel along the resistance 145. Let it be assumed that the bridge 130 is balanced so that the slider 146 is stationary in the position shown.

Under these conditions, assume that the temperature adjacent the resistance element 143 increases, thereby indicating a need for the operation of the valve mechanism 110 toward its closed position so as to decrease the supply of heating fluid to the space being controlled.

This increase in temperature adjacent the resistance element 143 causes an increase in the resistance of that element, thereby changing the division of the supplied potential between the two upper arms of the bridge circuit 130, and causing the potential of output terminal 133 to approach more closely the potential of input terminal 131. Since the potential of output terminal 134 remains substantially equal to the median potential of the supply, a difference of potential exists between the output terminals 133 and 134. This difference of potential is transmitted to the input terminals 11 and 12 of amplifier 10, and it produces a current flow in the circuit through the field winding 114 of motor 111, which is connected to output terminals 13 and 14 of amplifier 10. Field winding 115 of motor 111 is energized by current flowing from secondary winding 116 through condenser 122. The condenser 122 establishes the phase of the current flowing through winding 115 with respect to the phase of the terminal voltage of secondary winding 116. The phase of the current supplied to winding 114 is determined by the direction of unbalance of the bridge circuit 130 subject to modification by any phase displacement occurring in the amplifier 10. As previously stated, the phase displacement through the amplifier 10 may be controlled by proper design of the condensers 75 and 98. The design of condenser 122 is therefore coordinated with the design of condensers 75 and 98 so that a quadrature phase relationship is maintained between the currents flowing in the motor windings 114 and 115. In accordance with the well known characteristics of split phase motors, when currents of that character are supplied to the windings, rotation of the motor results in a direction dependent upon the sense with which the current in one winding is displaced in phase from the current in the other.

In the present instance, the relative phase displacement of the two currents, as determined by the direction of unbalance of the bridge circuit 130, is such that the motor 111 rotates in a direction to move the valve mechanism 110 towards closed position, thereby decreasing the supply of heat to the space adjacent the resistance element 143.

At the same time, the slider 134 is driven to the left along resistance 145, thereby causing the potential of output terminal 134 to approach the new potential of output terminal 133. The signal applied to the input terminals 11 and 12 of amplifier 10 is thereby decreased, and as it reaches zero the motor 111 stops and the bridge circuit 130 is rebalanced.

It will be readily understood that if the temperature adjacent the resistance 143 decreases, the potential of output terminal 133 approaches that of input terminal 132 more closely than the potential of output terminal 134, and that an alternating signal whose phase is displaced 180 degrees from the signal under the conditions previously discussed is applied to the input terminals 11 and 12 of amplifier 10. A current displaced 180 degrees from the current previously described therefore flows in winding 114. Since the phase of the current flowing in winding 115 is constant, the currents in the two windings are still displaced 90 degrees, but the displacement is now in the opposite sense. That is, current which formerly led the other current by 90 degrees now lags the other current by a similar angle. Therefore, the motor 111 rotates in the opposite direction, moving the valve mechanism 110 towards open position and driving the slider 146 to the right along resistance 145 until the bridge circuit 130 is rebalanced.

A well-known characteristic of split-phase motors of the type described is that the torque available at the rotor is a maximum when the currents supplied to the two stator windings are displaced in phase by exactly ninety electrical degrees. If the currents depart from this optimum displacement, the motor torque decreases as a function of the angle of such departure. If the departure continues until the currents are in phase or of exactly opposite phases, the torque is zero. If the departure from the optimum displacement continues in the same sense after the torque has been reduced to zero, the torque begins to increase again, but in the opposite direction.

It will therefore be readily understood that if the current supplied by the amplifier 10 to the winding 114 should shift in phase with respect to the current supplied to winding 115, the torque supplied by the motor 111 would be adversely affected.

If the amplifier output current should shift in phase by more than ninety degrees from its intended relationship, the direction of operation of the motor would be reversed. From the preceding description of the operation of the amplifier 10, it should be apparent that the automatic volume control arrangement provided therein prevents undesirable shifts in the phase of the current supplied by amplifier 10 to motor winding 115.

As previously described, the overall input potential-output current characteristic of the amplifier 10 is such that for small unbalances of bridge circuit 130, the output current of amplifier 10 increases rapidly, but that after a certain amount of unbalance has been reached, the output current increases no further. As a result of this characteristic, it may be seen that during the rebalancing operation of the system, the current flowing in the winding 114 rapidly approaches zero as the bridge circuit 130 approaches its balanced condition. Therefore, the motor is slowed down as it approaches the balance point of the system, and there is substantially no tendency for the motor to overrun its proper balance position.

Such an overrun might cause the unbalance of the bridge circuit to be reversed and produce a continuous oscillation or hunting of the motor.

While I have shown and described a preferred embodiment of my invention, other modifications thereof will readily occur to those skilled in the art, and I therefore intend my invention to be limited only by the appended claims.

I claim as my invention:

1. Control apparatus, comprising in combination, a device to be controlled, means including an electrical winding for controlling the operation of said device in opposite senses dependent upon the phase of alternating electrical energy supplied to said winding, means responsive to a condition indicative of the need for operation of said device for producing an alternating potential of magnitude variable in accordance with said condition and of a phase determined by the direction of departure of said condition from a predetermined value, means for amplifying said potential including a preliminary stage comprising an electrical discharge device and a later stage comprising two electrical discharge devices connected in phase opposition, each said discharge devices having an anode, a cathode, and a control electrode, an input circuit for each discharge device including its control electrode and cathode, an output circuit for each discharge device including its anode and cathode, means coupling said winding to the output circuits of said later stage, and means for limiting the current supplied to said winding so as to limit the undesired phase shift in said current, said last named means comprising an impedance, means connecting said impedance in at least one of said circuits of said later stage so as to produce across said impedance a unidirectional potential substantially proportional to the current flowing in said one circuit, means connecting the negative terminal of said impedance to the control electrode of said preliminary stage, and means connecting the positive terminal of said impedance to the cathode of said preliminary stage.

2. Control apparatus, comprising in combination, a device to be controlled, means including an electrical winding for controlling the operation of said device in opposite senses dependent upon the phase of alternating electrical energy supplied to said winding, means responsive to a condition indicative of the need for operation of said device for producing an alternating potential of magnitude variable in accordance with said condition and of a phase determined by the direction of departure of said condition from a predetermined value, means for amplifying said potential including a preliminary stage comprising an electrical discharge device and a later stage comprising two electrical discharge devices connected in phase opposition, each said discharge devices having an anode, a cathode, and a control electrode, an input circuit for each discharge device including its control electrode and cathode, an output circuit for each discharge device including its anode and cathode, inductive coupling means between said stages, further inductive coupling means between the output circuits of said final stage and said winding, and means for limiting the current supplied by said amplifier to said winding so as to limit the phase shift accompanying a changing flow of current through said inductive coupling means, said last named means comprising an impedance, means connecting said impedance in at least one of said circuits of said later stage so as to produce across

said impedance a potential substantially proportional to the current flowing in said one circuit, means connecting the negative terminal of said impedance to the control electrode of said preliminary stage, and means connecting the positive terminal of said impedance to the cathode of said preliminary stage.

3. Control apparatus, comprising in combination, a device to be controlled, reversible motor means for operating said device in opposite senses dependent upon the phase of alternating electrical energy supplied to said motor means, a normally balanced electrical network having a pair of output terminals and effective to produce at said output terminals an alternating electrical potential variable in magnitude in accordance with the unbalance of said network and of a phase determined by the sense of said unbalance, first impedance means connected in said network and variable in accordance with the magnitude of a condition indicative of the need for operation of said device to unbalance said network, second impedance means connected in said network and variable by operation of said motor means to rebalance said network, means for amplifying said potential including a preliminary stage comprising an electrical discharge device and a later stage comprising two electrical discharge devices connected in phase opposition, each said discharge device having an anode, a cathode, and a control electrode, an input circuit for each discharge device including its control electrode and cathode, an output circuit for each discharge device including its anode and cathode, means coupling the output circuit of said final stage and said motor means, and means for limiting the current supplied to said motor means by said final stage so as to limit the phase shift in said current occurring independently of the direction of unbalance of said bridge, said last named means comprising an impedance, means connecting said impedance in at least one of said circuits of said latter stage so as to produce across said impedance a potential substantially proportional to the current flowing in said one circuit, means connecting the negative terminal of said impedance to the control electrode of said preliminary stage, and means connecting the positive terminal of said impedance to the cathode of said preliminary stage.

4. A motor control system, comprising in combination, a motor having a plurality of electrical windings, means for energizing one of said windings from a source of alternating potential fixed in phase, means responsive to a condition indicative of the need for operation of said motor for producing an alternating electrical potential of magnitude variable in accordance with said condition, means for amplifying said potential including a voltage amplifying stage and a power amplifying stage, each said stage including at least one electrical discharge device having an anode, a cathode and a control electrode, means coupling the other of said windings to a circuit including the anode and cathode of said power amplifying stage, and means for limiting the current supplied by said power amplifying stage to said winding so as to decrease undesired phase shifting, said last named means comprising an impedance, means connecting said impedance in the path of at least a portion of the current flowing in the device of said power amplifying stage so as to produce thereacross a unidirectional potential substantially proportional to said current, and means connecting the negative terminal of

said impedance to the control electrode of said voltage amplification stage and the positive terminal of said impedance to the cathode of said voltage amplification stage.

5. Control apparatus, comprising in combination, a device to be controlled, an electrical winding for controlling the operation of said device and effective to cause operation of said device in a manner dependent upon the phase relationship between the voltage applied to said winding and a voltage fixed in phase, means responsive to a condition indicative of the need for operation of said device for producing an alternating potential of magnitude variable in accordance with said condition, means for amplifying said potential including a preliminary stage comprising an electrical discharge device and a later stage comprising two electrical discharge devices connected in phase opposition, each said discharge device having an anode, a cathode and a control electrode, an input circuit for each discharge device including its control electrode and cathode, an output circuit for each discharge device including its anode and cathode, the corresponding circuits associated with said two discharge devices in said later stage having respective common portions, means coupling said winding to the output circuits of said later stage, and means for limiting the current supplied to said winding by said later stage so as to limit undesired phase shifts in said current, said last named means comprising an impedance, means connecting said impedance in one of said common portions so as to produce across said impedance a unidirectional potential substantially proportional to the current flowing in said later stage, and means connecting the negative terminal of said impedance to the control electrode of said preliminary stage.

6. Control apparatus, comprising in combination, a device to be controlled, an electrical winding for controlling the operation of said device and effective to cause operation of said device in a manner dependent upon the phase relationship between the voltage applied to said winding and a voltage fixed in phase, means responsive to a condition indicative of the need for operation of said device for producing an alternating potential of magnitude variable in accordance with said condition, means for amplifying said potential including a preliminary stage comprising an electrical discharge device and a later stage comprising two electrical discharge devices connected in phase opposition, each said discharge device having an anode, a cathode and a control electrode, an input circuit for each discharge device including its control electrode and cathode, an output circuit for each discharge device including its anode and cathode, the corresponding circuits associated with said two discharge devices in said later stage having respective common portions, means coupling said winding to the output circuits of said later stage, and means for limiting the current supplied to said winding by said later stage so as to limit the amount of undesired phase shift, said means comprising an impedance, means connecting said impedance in the common portion of said later stage input circuits, so as to produce across said impedance a unidirectional potential substantially proportional to the current flowing therein, and means connecting the negative terminal of said impedance to the control electrode of said preliminary stage.

7. In combination, an electronic amplifier including a preliminary stage comprising an electrical discharge device and a later stage comprising

ing two electrical discharge devices connected in phase opposition, each said discharge device having an anode, a cathode, and a control electrode, an input circuit for each of said last named two discharge devices including its control electrode and cathode, an output circuit for each discharge device including its anode and cathode, the corresponding circuits associated with said two discharge devices in said later stage having respective common portions, and current limiting means for said amplifier comprising an impedance connected into the common portion of said input circuits so as to produce across said impedance a unidirectional voltage drop substantially proportional to the current flowing in said common portion of said input circuits whenever said control electrodes are at a potential higher than that of said cathodes, and means for applying to the input circuit of said preliminary stage a biasing voltage dependent upon the voltage drop across said impedance, said biasing voltage acting to decrease the potential of the control electrode of said preliminary stage upon an increase in the voltage drop across said impedance.

8. In combination, an electronic amplifier including a preliminary stage comprising an electrical discharge device and a later stage comprising two electrical discharge devices connected in phase opposition, each said discharge device having an anode, a cathode, and a control electrode, an input circuit for each of said last named two discharge devices including its control electrode and cathode, an output circuit for each discharge device including its anode and cathode, the corresponding circuits associated with said two discharge devices in said later stage having respective common portions, the control electrodes of said last named two discharge devices being maintained at potentials sufficiently close to cathode potential that the application of a signal voltage to the control electrodes causes them to assume potentials positive with respect to their associated cathodes, current limiting means for said amplifier comprising an impedance connected into the common portion of said input circuits so as to produce across said impedance a unidirectional voltage drop substantially proportional to the current flowing in said common portion of said input circuits whenever said control electrodes are at a potential higher than that of said cathodes, and means for applying to the input circuit of said preliminary stage a biasing voltage dependent upon the voltage drop across said impedance, said biasing voltage acting to decrease the potential of the control electrode of said preliminary stage upon an increase in the voltage drop across said impedance.

9. In combination, an electronic amplifier including a preliminary stage comprising an electrical discharge device and a later stage comprising two electrical discharge devices connected in phase opposition, each said discharge device having an anode, a cathode, and a control electrode, a coupling transformer having a primary winding and a center tapped secondary winding, means for energizing said primary winding from the output of said preliminary stage, an input circuit for each of said last named two discharge devices including its control electrode and cathode and one half of the secondary of said coupling transformer, an output circuit for each discharge device including its anode and cathode, the corresponding circuits associated with said two discharge devices in said later stage having respective common portions, and current limiting means

for said amplifier comprising an impedance connected into the common portion of said input circuits between the center tap of said secondary winding and the cathodes so as to produce across said impedance a unidirectional voltage substantially proportional to the current flowing between said center tap and said cathodes whenever said control electrodes are at a potential higher than that of said cathodes, means connecting the negative terminal of said impedance to the control electrode of the discharge device of said preliminary stage, and means connecting the positive terminal of said impedance to the cathode of the discharge device of said preliminary stage.

10. Motor control apparatus, comprising in combination, a motor to be controlled and having only two windings one of which is connected to a voltage source fixed in phase, means including a balanceable network for producing an output voltage whose magnitude and effective direction are dependent upon the extent and the direction of unbalance of said network, means for amplifying said voltage including a preliminary stage comprising an electrical discharge device and a final stage comprising two electrical discharge devices connected in phase opposition, each said discharge device having an anode, a cathode and a control electrode, an input circuit for each discharge device including its control electrode and cathode, an output circuit for each discharge device including its anode and cathode, the input and output circuits of said final stage each constituting a pair of corresponding circuits, means for applying to the input circuit of said preliminary stage a voltage dependent upon the voltage produced by said balanceable network, means for

coupling the output circuit of said preliminary stage to the input circuits of said final stage in such a manner that upon said network being unbalanced said discharge devices of said final stage are rendered conductive in a manner depending upon the direction of unbalance of said network, a coupling transformer comprising a primary winding having two portions each connected into one of said output circuits of said final stage and a secondary winding connected to said other motor winding so that said winding is energized with current reversible in phase depending upon the direction of unbalance of said bridge, and feedback means comprising impedance means so connected to both circuits of one of said pair of circuits of the final stage as to have a D. C. voltage drop thereacross whenever the network is unbalanced, and means for employing the voltage drop developed across said impedance means to 20 reduce the voltage supplied to said preliminary stage.

ALBERT P. UPTON.
